UNITED STATES PATENT OFFICE.

JOHN O. DONNER, OF WILLIAMSBURG, AND SAMUEL S. HEPWORTH, OF YONKERS, NEW YORK,

IMPROVEMENT IN THE MANUFACTURE OF HARD SUGAR.

Specification forming part of Letters Patent No. 124,197, dated March 5, 1872.

SPECIFICATION.

To all whom it may concern:

Be it known that we, JOHN O. DONNER, of Williamsburg, in the county of Kings and State of New York, and SAMUEL S. HEPWORTH, of Yonkers, in the county of Westchester and State of New York, have invented certain new and useful Improvements in the Art of Making Hard Sugar; and we do hereby declare that the following is a full, clear, and exact description of the same, whereby a person skilled in the art can make and use the same, reference being had to the accompanying drawing and to the letters of reference marked thereon.

Like letters in the figures indicate the same parts.

Our invention consists in certain methods, means, and appliances for making hard sugar directly in a centrifugal machine, so that it can be taken out of the machine in solid blocks. Heretofore all sugar made in centrifugal machines has been of the soft variety, more or less moist from the sirup or liquor remaining in it when it is taken from the machine, requiring a subsequent drying or crystallizing process if it is desired to change its character. Hard or loaf-sugar has been manufactured heretofore by pouring the magma of crystals and sirup as it comes from the vacuum-pan, at a temperature of from 150° to 205° Fahrenheit, into suitable molds, in which crystallization is perfected. This crystallization takes place by cooling down such "magma" or mixture of crystals and sirup. As it gradually cools smaller crystals are formed, binding the larger ones—those formed in the vacuum-pan—together. At a certain stage of the process the uncristallized sirup is drawn off by means of a hole in the bottom of the molds. After this has been done a colorless saturated solution of sugar is run through the molds, at a low temperature rendering the sugar white, and forming minute crystals which harden the whole mass. The molds are allowed to drain clearly or quite dry, when the loaf of hard sugar is knocked out of the mold and placed in a kiln to expel any remaining moisture. The washing-liquor in this process is used at a low temperature, for the reason that if

poured onto the sugar hot the cool sugar would so lower its temperature as to precipitate a sufficient number of small crystals to choke the mold and prevent the liquor running through. Soft sugar is sometimes hardened by being pressed under a great pressure and then dried; but this sugar is never quite hard for want of the minute crystals which are formed in the foregoing process.

In our improved method of making hard sugar we are obliged to use a centrifugal machine of special construction, or make essential modifications of such machines as are now used, in order to be able to remove the hard sugar from the machine after it is made. This we will proceed to describe.

Figure 1 is a cross-section through the shaft and basket of our improved machine. Fig. 2 is a horizontal section through the basket, showing the compartments. Fig. 3 shows one section or box, such as would be placed in an ordinary centrifugal machine to adapt it to our improved process. Fig. 4 shows the same divided into smaller compartments.

The revolving basket *a b*, the spindle *c*, the outside trough *d* for receiving the liquor thrown off, the frame *f f*, and the pulley *e* for driving the machine are constructed in the manner usual in centrifugal machines, except that the top flange of the basket is left off and a band of angle-iron placed around the top of the basket outside of the cylindrical portion. Inside of the basket is a removable part consisting of a bottom plate, *g*, which is made of cast metal, of a similar shape to the bottom plate of the basket, and has a circular aperture in the middle to fit the shaft or spindle, the vertical division-plates *h h*, which lie in radial lines and touch the cylindrical portion of the basket, and a top ring or flange, *i*, the upper face of which is flush with the top of the revolving basket. This flange may be made of copper, brass, or any other suitable metal. The vertical division-plates may be placed at any desired distance apart, or may have horizontal plates between them, as shown in Fig. 4. That part of the revolving basket usually made cylindrical may be made slightly conical, if desired, for facility in removing the internal part last described. A cover, *j*, is made to fit tightly down upon the top of our improved

machine, and to be held firmly by being secured to the central spindle or to the outside edge of the basket. The upper part of the spindle is made hollow, and has small apertures *n* leading into the interior of the basket, as shown in the drawing. These are for the purpose of admitting liquor, air, or steam, as hereinafter described.

Our method of operating to produce hard sugar with the above-described machine is as follows: We prepare a magma of sugar consisting of a saturated solution, at a high temperature, mixed with crystals of sugar of a lower temperature, and place a sufficient quantity in the machine to fill all the cells above described. After it is put in through the opening in the top of the removable part above described the top plate is placed over it and firmly secured in its place. The machine is then rapidly revolved in the usual manner. The centrifugal force causes the syrup to pass through the sugar and be thrown out through the perforated plate *b*. The reduction of the temperature of the saturated solution, by passing through the cooler crystals of sugar, causes a great number of small crystals to form, which binds together the whole mass and renders it hard; or the machine may be filled with a magma of a uniform temperature, such as is ordinarily worked in centrifugal machines, and after the syrup has been expelled by rapid revolution a saturated solution of sugar, at a high temperature, can be introduced through the central opening, which cools as it passes through the sugar already formed and deposits the small crystals to render it hard.

It will be observed that our improved process depends upon the reduction of the temperature of the syrup contained in the magma while revolving in the centrifugal machine. Warm air or steam can also be introduced through the central apertures to dry the sugar in the machine, and a moderately hard sugar may be formed by passing hot air or steam through sugar formed in the ordinary way in our improved machine. After the hard sugar is

formed the cover and interior part are removed and the blocks of sugar knocked out from the cells and further dried in kilns, or treated in the ordinary manner of preparing hard sugar for sale.

We do not confine our invention to the particular machine above described, nor to the shape or construction of the cells in which the hard sugar is formed, as various devices may be easily contrived answering the same purpose. Our invention can be easily adapted to machines of other construction, or to those that are now in use, by inserting within them sectional cells or frames, such as are shown in Figs. 3 and 4, which are placed around the circle inside of the perforated cylindrical sides of the machine, and, when filled with hard sugar by our improved process, can be removed from the machine to take out the sugar. These cells can be made of various sizes and depths, according to the size and shape of the blocks of sugar desired.

Claims.

What we claim as our invention is—

1. The preparation of hard sugar in a centrifugal machine by the use of a magma consisting of a saturated solution of sugar, at a higher temperature, mixed with crystals of sugar of a lower temperature, substantially in the manner herein specified.
2. The preparation of hard sugar in a centrifugal machine by passing a saturated solution of sugar, at a higher temperature, through soft sugar already formed in the machine at a lower temperature, substantially in the manner herein described.
3. The interior removable frame *g h i* in combination with the basket of a centrifugal machine, substantially as herein specified.
